UNITED STATES PATENT OFFICE

2,505,805

KNOCKDOWN PIANO

Charles Frederick Stein, La Grange, Ill., assignor
to Pratt, Read and Company, Inc., Ivoryton,
Conn., a corporation of Connecticut

Original application December 21, 1946, Serial
No. 717,678. Divided and this application Feb-
ruary 20, 1948, Serial No. 9,785

4 Claims. (Cl. 84—174)

1

This invention relates in general to pianos and more particularly to a piano structure including a plurality of pre-assemblies which lend themselves to high speed production methods and which are so constructed that manufacture, shipping and storage of a high quality piano is made easier. This application is a division of my application Serial No. 717,678, filed December 21, 1946.

In the prior art it has been the general practice to manufacture pianos on an individually customized basis. This has been due primarily to the nature of prior art piano construction and due to the difficulty of producing, in such construction, a piano of the desired quality and performance. Although various attempts have been made to speed up piano manufacture and to apply high speed production assembly line methods thereto, due to the requirement of hand fitting a great many parts of the piano, these methods have still resulted in pianos which are considerably different and in which the tone and performance vary depending upon the individuals who worked upon them.

Another reason why high speed manufacturing methods have not been satisfactory for the manufacture of pianos is that in most commercial piano structures, the piano casing is used for assembling many of the parts of the piano into a complete structure. For this reason special care must be taken of the piano casing during manufacture, assembly and adjustment of the piano, to prevent damage thereto. Even when taking such precautions, it is necessary that the casing be refinished after manufacture of the piano has been completed. The practice of forming the piano case and operating structure into one complete unit has also complicated shipment and storage of pianos because of the great weight and bulk of the completed piano structure. Piano construction in which the operating structure and casing are made in one composite unit is subject to another defect, that is, that the piano operating mechanism has a relatively long life and the casing becomes out of style while the piano is still in good condition. As the casing is used to support the operating structure, it is very difficult to remove the same and apply a new casing to thereby improve the appearance of the piano.

Prior commercial piano constructions are also objectionable in that the completed piano is very heavy and hard to handle. This is caused by the fact that in order to provide means sufficiently rugged for stretching the strings of the piano, a

2

metal string plate together with a massive wooden back structure have been required. As the casing is used to support this back structure and also the various operating parts of the piano, it has had to be constructed in a very rugged manner further increasing the weight of the piano.

My Patent No. 2,431,350 and my copending applications, Serial Nos. 585,053 and 643,713, are directed to knock down piano-structures which overcome some of the above mentioned difficulties with reference to piano construction. The structure disclosed in this application includes improvements and further features not disclosed in the above applications.

It is an object of this invention, therefore, to provide a new and improved knock down type piano in which the operating structure of the piano and the case therefor are independent and can be easily assembled and disassembled.

A further object of this invention is to provide a piano having an operating structure which is independent of a casing therefor, and in which the operating structure is arranged so that a minimum amount of space is required for shipping and storing the same.

A still further object of this invention is to provide a piano having a self-supporting operating structure and a case composed of a plurality of parts which are assembled together as the case is applied to the operating structure.

A feature of this invention is the provision of a single metal frame member for a piano on which all the operating components of the piano are mounted and which is self-supporting to provide a structure which can be completely adjusted and assembled without the use of the piano casing.

A further feature of this invention is the provision of a piano operating structure having a horizontal string chassis with brackets removably mounted thereon and a piano keybed pivotally secured to the brackets so that the keybed can be moved from a normal position for playing the piano to a position parallel with and adjacent the string chassis so that a minimum amount of space is required for shipping and storing the operating structure.

Further objects, features and advantages will be apparent from a consideration of the following description taken in connection with the accompanying drawings in which:

Fig. 1 is an exploded view showing the operating structure and removable casing in accordance with this invention;

Fig. 2 is an exploded view of the back portion

Fig. 3 is a rear view of the back portion in assembled form;

Fig. 4 is a cross-sectional view of the back portion;

Fig. 5 illustrates the two positions of the keyboard; and

Fig. 6 shows a portion of the keyboard and mounting therefor.

In practicing my invention I provide a low upright piano having a back portion including a single frame member with a sounding board and strings secured thereto. The frame member includes means for securing the piano action thereto and brackets which are removably secured to the frame member for supporting the keyboard of the piano. The keyboard is pivotally mounted on the brackets so that it may be positioned in the normal operating position with respect to the piano action or pivoted to a position parallel to the frame member and adjacent the piano action to thereby provide a piano structure which may be shipped and stored in a minimum of space and in which the keyboard tends to protect the piano action and the keys. A removable supporting foot is provided on the frame so that the operating structure may be held in an upright position thereby. A casing is provided for the piano including a plurality of members which are assembled as they are attached to the operating structure of the piano. Provisions are included on the frame member for attaching the casing thereto.

Referring now more particularly to Fig. 1, there is shown a piano operating structure 10 including a back portion 11. A piano action 12 and keyboard 13 are secured to the back portion, the keyboard being supported by brackets 14. A supporting foot 15 is also secured to the back structure for a purpose to be described hereinafter. Members adapted to form a casing are provided including sides 16, top member 17, shelf 18, music desk 19, fall boards 20, key blocks 21, key slip 22, toe rail 23, bottom panel 24, legs 25 and lyre 26. These various members are adapted to be secured together as the casing is applied to the operating structure.

As is shown in Fig. 1, the piano back portion 11 has openings 30 therein adapted to receive dowels 31 on the sides 16 of the case to thereby position the sides with respect to the operating structure. Registering hinge-like portions 32 and 33 are provided on the frame and sides respectively for securing the sides to the frame, pins 34 being provided to connect the hinge portions to thereby form simple and effective securing means. After the sides have been secured to the operating structure, the legs 25 are secured to the keybed 13 by screws or other securing means, projections 35 being provided in the legs to fit in openings 36 in the keybed for positioning the legs with respect thereto. The toe rail 23 is then secured to the side members 16 with the channel members 37 thereon being positioned about projecting portions 38 on the sides and pins 39 being positioned in openings in the members 37 and 38 to hold the toe rail securely to the side member. Thereafter the bottom panel 24 may be secured in place with respect to the toe rail 23 and sides 16 by any suitable securing means, this member being removable in the usual piano construction.

The key blocks 21 and the key slip 22 may now be set in place, supporting members 40 being provided on the sides of the casing 16 to which these members may be secured by screws or other securing means. The key blocks 21 include re-

cesses 41 therein so that the fall board 20 may be supported on the blocks and held in place in the recesses. The shelf 18 is supported in position on blocks 42 secured to the side members 16 with pins 43 being provided in projections on the shelf which fit into openings 44 in the side members to hold the shelf in place. When the shelf is in position, the music desk 19 may be placed thereon and secured thereto as by screws. The top panel 17 of the piano includes hinge portions 45 adapted to cooperate with similar portions 46 on the frame 11, the hinge portions being connected by pins 47 forming a hinged connection for the top panel.

It is obvious that the various parts of the case described above can be of such configuration that the assembled case will be of any desired designs, such as the various 18th century designs or modern designs. As cases of the various designs may be applied to the same operating structure, it will be possible for the owner of a piano to have his piano restyled by changing the case thereof, without removing the piano from his home. Also, sales agencies can change the cases of pianos to suit the desire of the purchaser and thus reduce the number of pianos which they must keep in stock.

Reference is now made to Figs. 2, 3 and 4 in which the details of the back portion of the operating structure are illustrated. The back portion includes a frame member 50 which is the sole supporting member for the entire operating structure for the piano. As indicated in Figs. 2 and 4 the frame includes a peripheral flange portion 51 and a central web portion 52 having a plurality of reinforcing ribs 53 thereon and openings 54 therein. The reinforcing ribs 53 are so positioned to strengthen the frame at the points where the tension of the piano strings cause the greatest stresses therein. A cross-rib 55 is provided across the back of the frame member 50 forming a narrow upper recess and a relatively large rectangular lower recess. A pin block 56 is positioned in the upper recess and a sounding board 57 is supported in the lower recess. Openings 58 are provided in the web portion at the upper recess through which pins 59 extend into the pin block 56 for supporting the piano strings 60. Projections 61 are provided on certain of the reinforcing ribs on the frame for supporting the other ends of the strings.

The sounding board 57 includes a relatively thin vibrating member 62 having a surrounding frame portion 63 which fits into the recess between the cross-rib 55 and the peripheral flange on the bottom and sides of the frame member. The sounding board is held in position by screws 64 which are threaded into openings 65 in the web portion 52 adjacent the periphery thereof. Ribs 66 are provided on the back side of the sounding board for stiffening the same and bridges 67 and 68 are provided on the front side in such a manner that they extend through openings 54 in the web portion of the frame to contact the strings 60. Fig. 4 shows a cross-sectional view of the frame member 50 with the pins 59, strings 60 and sounding board 57 in place. Fig. 2 shows the manner in which the bridges 67 and 68 on the sounding board project through the openings 54 in the web portion.

As previously stated, the frame member 50 of the back portion 11 forms the support for the entire operating structure of the piano. Figs. 1 and 5 illustrate the operating structure assembled on the frame member 50. As shown in the

drawings, the frame 50 has a removable foot 15 secured thereto which is used to support the back portion of the piano in the normal upright position. A projection 70 is provided on one of the reinforcing ribs 53 of the frame member having an opening 71 therein in which the foot 15 is removably positioned. The foot is bent and may be placed in the opening 71 at different angles so that the frame member 50 may be tilted more or less (Fig. 5). A rubber tip 72 is provided on the foot to provide a secure contact with the supporting surface. The foot is adapted to hold the back portion, or the entire operating structure of the piano in the normal upright position while other supporting means are secured thereto.

The piano action 12, which is provided as a preassembled unit, includes a plurality of supporting brackets 86 adapted to support the action on the frame 50. Integral projections 80 are provided on the reinforcing ribs 53 of the frame (Fig. 2) for supporting a horizontal bar 81 which is provided for supporting the piano action in operative position with respect to the strings. Forwardly extending projections 83 and pins 85 which project upwardly are provided on the horizontal bar 81. The bottoms of the action brackets 86 include recesses adapted to fit over the pins 85 to thereby mount the action on the bar 81. The top portions of the brackets 86 are supported on the web portion 52 of the frame 50 by pins 87. Accordingly, it is seen that the action is supported entirely on the frame member 50 and may be connected thereto or removed therefrom as a unit after having first been preassembled. It is to be noted that the action fits closely to the web portion 52 and a portion thereof is within the space defined by the flange 51 of the frame. This provides an operating structure of minimum depth.

In Figs. 5 and 6, there is illustrated the manner in which the keyboard 13 is supported on the frame member 50. The keyboard includes a keybed 94 on which the piano keys 95 are supported in a manner well known in the art. Brackets 14 are removably secured to the flange 51 of the frame member by screws 90, the brackets having portions 91 which abut the flange to thereby make a very rigid connection. The brackets 14 include U-shaped trunnions 92 on the inside of the forwardly extending portions thereof. Pins 93 are provided on the keyboard 13 positioned to engage the trunnions 92 to thereby pivotally support the keyboard on the brackets. This is clearly illustrated in Fig. 6. The keyboard may thus be pivoted from a vertical position as shown in solid lines in Fig. 5 to a horizontal position shown in dotted lines in Fig. 5. In the vertical position the operating structure of the piano may be stored or shipped in a relatively small space with the keybed 94 tending to protect the keys 95 and the action 12. In the horizontal position, the keybed and keys are in the normal playing condition with the capstan screws 96 at the back end of the keys engaging the whips 97 of the piano action. It is to be understood that the particular action disclosed and the cooperation between the keys and action is merely illustrative and other types of actions might be used in the same arrangement.

Means are provided for locking the keyboard in the two positions, comprising bolts 98 on the keyboard registering with openings 99 on the bracket 14. Additional bolts may be positioned in the keybed intermediate the ends thereof registering with openings in the projections 83.

Wing nuts 101 are provided on the bolts for securely supporting the keyboard in the horizontal playing position. When it is desired to pivot the keyboard, the nuts 101 are removed and the keyboard pivoted in the trunnions 92 to the vertical position. The trunnions 92 and the pins 93 on the keyboard have openings therein which register when the keybed is in the vertical position. Pins 102 are provided which may be positioned in the openings to lock the keyboard in the vertical position. This arrangement is clearly shown in Fig. 5.

In manufacturing a piano in accordance with the invention, the back portion is first assembled 15 with the pin block 56 and sounding board 57 being secured to the frame 50 and the strings 60 strung thereon. Thereafter the foot 15 is secured in place on the frame and the brackets 14 for supporting the keybed are applied. With the back portion held in upright position the piano action 20 and keyboard are applied and the piano is completely regulated. It is apparent that a completely playable piano is thus provided which does not include any parts of the piano case. If it is now desired to ship or store the piano, the keyboard may be pivoted to the vertical position and the foot 15 removed to thereby permit storing the operating structure in a minimum of space. When it is desired to assemble the operating 25 structure and case as a complete piano, the operating structure is again supported in the upright position by the foot 15, the keyboard is pivoted to the normal horizontal position, and the case is then applied thereto as previously described. It 30 is to be pointed out that after the legs 25 of the piano case are secured to the keyboard, the foot 15 can be removed and bottom panel 24 put in place.

It is seen from the foregoing that in accordance 35 with the invention a structure is provided wherein a piano may be assembled from a plurality of preassembled units each of which is adapted for production line manufacturing methods. The back portion is formed with a 40 single frame member which replaces the usual string plate and wooden back structure, and as this frame member may be cast as a single member, the manufacture thereof is simplified to a large extent as compared with former structures. The use of the frame member of the back portion 45 as the sole supporting member of the operating structure of the piano makes it possible to completely assemble the operating structure before applying a case thereto for styling the piano. The provision of the removable foot on the frame 50 member facilitates handling of the operating structure during the various manufacturing and assembling processes. The pivoted keyboard support results in an operating structure which requires less space for shipping and storage thereof 55 and in general permits the shipping and storage of two pianos in the space previously required for one.

The case for the piano disclosed, which is made 60 of a plurality of parts which are assembled as the case is applied to the operating structure, permits very easy and fast changing of cases on an operating structure. This not only has the advantage of eliminating damage to the case during 65 the manufacture of the operating structure but also results in the requirement of less shipping and storage space as the operating structure and various components of the case can be placed in much less space than is required for the completely assembled piano and case. The provision

of interchangeable cases has the further advantage of permitting the user of a piano to restyle a piano to conform with other decorations in his home and also permits selling agencies to furnish the cases desired by a particular purchaser without having a great number of pianos in stock.

It is, therefore, seen that I have provided a piano structure in which the various components are so designed that assembly and regulation of the operating parts are very easily accomplished. The structure is such that a minimum amount of shipping and storage space is required and that the complete unit can be assembled very rapidly by relatively unskilled workmen. The regulation of the piano is not affected by the assembly of the operating structure with respect to the case as the piano is complete and entirely playable without the case.

Although I have described certain embodiments of the piano structure in accordance with the invention, it is obvious that various changes can be made therein without departing from the intended scope of the invention as defined in the appended claims.

I claim:

1. A piano operating unit adapted for use with case means, said operating unit being playable and entirely self-supporting without having case means therewith and including in combination a unitary string chassis having a single flanged frame, a sounding board, strings, and means for supporting said sounding board and strings on said frame in the space defined by said flanges, a piano action in operative relation with said strings, means for supporting said piano action on said string chassis, bracket means, means for supporting said bracket means on said string chassis, a playing portion including piano keys, and means for pivotally supporting said playing portion on said bracket means so that said playing portion is movable from a horizontal position in which the keys are in position to operate said piano action to a vertical position in which the playing portion is adjacent said piano action to thereby form a compact unit with said playing unit being positioned to protect said action.

2. A piano operating unit adapted for use with case means, said operating unit being playable and entirely self-supporting without having a case means therewith and comprising a string chassis including a single flanged metal frame member, strings, a sounding board and means for supporting said strings and sounding board on said frame member in the space defined by said flanges, a playing portion including key support means and key means thereon, bracket means, means for mounting said bracket means on said frame member out of contact with the strings, means pivotally mounting said playing portion on said bracket means, and means secured to said frame member for supporting said operating unit independently of a case means, said playing portion extending perpendicular to said string chassis when in playing position and being pivotable to a position parallel to said string chassis to permit storage or transportation thereof in a relatively small space.

3. A piano operating unit adapted for use with case means, said operating unit comprising a back portion including a frame, strings and a sounding board, a piano action in operating position with respect to said strings, means for mounting said piano action on said frame, bracket means, means for securing said bracket means to said frame, a playing portion including piano keys thereon, means pivotally mounting said playing portion on said bracket means, supporting means removably secured to said frame, said playing portion and said supporting means having operating positions in which said keys are in normal operating position with respect to said action and said supporting means supports said operating unit to provide a complete playable unit, and non-operating positions in which said playing portion is pivoted toward said back portion and said supporting means is removed so that said operating unit forms a compact assembly.

4. A piano operating unit adapted for use with case means, said operating unit comprising a back portion including a single frame member with strings and a sounding board thereon, piano action means in operating position with respect to said strings, means for removably mounting said piano action means on said frame, bracket means, means for removably securing said bracket means to said frame member, a playing portion having key support means and key means thereon, means pivotally mounting said playing portion on said bracket means, and supporting means removably secured to said frame, said playing portion and said supporting means having a first position in which said key means are in normal operating position with respect to said action means and said supporting means supports said operating unit so that it is completely playable and entirely self-supporting and a second position in which said playing portion is pivoted toward said back portion and said supporting means is removed so that said operating unit forms a compact assembly which can be housed in a minimum amount of space.
